UNITED STATES PATENT OFFICE.

CHARLES H. GAIL, OF CHICAGO, ILLINOIS.

WIRE COUCH FABRIC.

1,087,755.

Specification of Letters Patent.

Patented Feb. 17, 1914.

Application filed January 13, 1913. Serial No. 741,664.

To all whom it may concern:

Be it known that I, CHARLES H. GAIL, a citizen of the United States, residing at Chicago, in the county of Cook and State of Illinois, have invented certain new and useful Improvements in Wire Couch Fabrics, of which the following is a specification.

My invention relates to improvements in wire couch fabrics, and has for one of its objects to provide, for beds or couches, a fabric that is practically inextensible but flexible in all directions and readily foldable longitudinally and transversely.

Another object of my invention is to provide, in a fabric of this character, composite members or links of such nature that most of the metal of which they are composed lies in substantially the shortest path between points upon which strain is imposed so that the links will not materially change their form or configuration when strained beyond the bending point of the wires of which they are made, thereby to preserve the original dimensions of the fabric without elongation, buckling, or sagging in either direction.

Another object of my invention is to provide a fabric of this general character in which the longitudinal marginal edges are in substantially straight lines.

Still another object of my invention is to provide a fabric composed of a small variety of parts thereby to simplify the structure and to contribute toward cheapening the operation of assembling the parts.

A further object of my invention is to provide a fabric wherein each part is of substantially symmetrical shape, adapted easily to be made by automatic machinery, and with each part having therein only simple bends which do not unduly strain the wire, so that relatively cheap, or low-grade wire will be used without sacrifice of strength.

Another object is to so interrelate the parts that each part is positioned against displacement or detrimental change of shape under the effect of heavy usage.

Other and further objects of my invention will become readily apparent to persons skilled in the art from a consideration of the specification when taken in conjunction with the drawing, wherein—

Figure 1 is a plan view of a piece of the fabric, showing one selvage edge; Fig. 2 is

an enlarged perspective view of several of 55 the links.

In both views the same reference characters are employed to indicate similar parts.

My fabric is made up of relatively elongated, longitudinally disposed members 5; 60 generally similar transversely disposed members 6; and intermediate connecting links 7 of generally rhombic or diamond shape.

The members 5 are made, preferably, by 65 centrally folding a wire upon itself to form a rather elongated U-shaped structure having a closed end and substantially parallel straight limbs with hooks 8 in their free ends. These are the links of the first order. 70 The intermediate connectors or members 7 are the links of the second order. They are each made by bending a wire into a shape substantially that of a rhomb, the links being quadrangular in outline and having 75 its free proximate ends formed into hooks 9. The hooks 9 of links 7 engage the closed end 10 (which in this respect may be considered as a hook) of the adjacent link 5, and the hooks 8—8 of member 5 engage the angle 11 80 of the connector 7. The transverse links or tie wires 6 of the third order are provided with hooks 12 which engage the angles 13—13 of the connectors. The selvage connectors 14, preferably, are triangular in out- 85 line, so as to provide, with the links 5, a substantially straight selvage edge.

It will be observed that when strain is imposed upon the fabric, as by a superimposed weight, the resultant lines of strain 90 will be in substantially the plane of the body portions of the quadrangular connector members. It is also to be observed that the strain passes through the relatively elongated links in linear directions. There is 95 therefore no substantial strain imposed upon any member of the fabric in such manner as to distort, or tend to distort, or change the configuration of, any of them. For the reason that the members are originally of 100 that shape best calculated to withstand the strain, the body portions whereof are located in the shortest path between adjacent points at which other members are connected, there will be no material expansion 105 of the fabric to cause slack or buckling. All parts of the upper surface of the fabric will remain substantially in a single plane

when relieved of the weight that may be imposed upon it. This is due to the fact that there is no extension of the parts or any of them when loaded to their load-bearing capacity.

In order to provide a smoother even top surface, the hooks, which are located at the terminals of each of the three members of the structure, are downturned and therefore the top surface of the fabric has no raw edges.

The terminal links 5 of the structure are connected to the usual closed helical springs 15. These springs exert a considerable 15 silent tension upon the respective chains of the fabric, composed of the longitudinally extending links 5 and the connectors 7, and serve to draw each of the chains back into its horizontal position after the weight that 20 may have been placed on the fabric has been removed.

Owing to the fact that each of the elements of my structure is adapted not to be stretched or elongated by superimposed 25 weight, the springs 15 are adapted to bring back into the normal plane each of the chains or longitudinally extending series of links.

While I have herein shown a single embodiment of my invention for the purpose 30 of clear disclosure, it is evident that many changes may be made within the structure without departing from the spirit and scope of the appended claims; for instance, the 35 links 5 may be made of a single wire, as are the links 6, and other changes may naturally suggest themselves to persons skilled in the art within the spirit of my invention and within the scope of the appended claims.

40 What I claim is:

1. A wire fabric composed of three sets 45 of parts, namely longitudinally extending wire links having end hooks, transversely extending wire links having end hooks, and quadrangular wire connectors, each said connector having two end hooks at one angle

embraced by an end hook of one of the proximate links and its remaining angles receiving end hooks of the remaining proximate links, the sides of said connector lying 50 in substantially the shortest paths between the points of strain imposed on said links.

2. A wire fabric composed of a plurality of chains of alternate similar members of the first and second orders, each member of the first order comprising a wire link having its ends bent back to form engaging parts or hooks, and each member of the second order comprising a single-wire link having hooks at its two ends brought close together, 55 said hooks jointly engaged by an end hook of one of the proximate members of the first order, and the opposite portion of the member of the second order engaged by an end hook of the remaining proximate member 60 of the first order; and wire tie links connecting the members of the second order of transversely adjoining chains.

3. A wire fabric comprising a plurality of chains of alternately similar members of the first and second orders, each member of the first order being a relatively long narrow link of wire doubled and bent to provide closed end and two substantially parallel straight limbs each having a hook at its 75 free end; each member of the second order comprising a rhombic wire link with hooks at its ends lying side by side at one angle, the closed end of each member of the first order engaging both hooks of a member of 80 the second order and having its end hooks engaging the opposite angle of another member of the second order; and transverse links having end hooks engaging the remaining angles of members of the second 85 order lying in adjacent chains.

In testimony whereof I hereunto set my hand in the presence of two witnesses.

CHARLES H. GAIL.
